UNITED STATES PATENT OFFICE

2,339,962

CONTROL MEANS FOR ROLL FEEDS

Charles V. St. Louis, Chicago, Ill., assignor to
Benjamin A. Tetzlaff, Riverside, Ill.

Application September 27, 1941, Serial No. 412,653

14 Claims. (Cl. 164—89)

This invention relates generally to new and useful improvements in control means for roll feeds for punch presses, and the like, adapted for controlling the accurate feeding of stock, as for example, coiled stock mounted on reels, whereby the forward feeding movement of the stock by the roll feed is arrested and fed responsively to the operation of the novel feed control means at predetermined intervals during the uninterrupted operation of the press, and during the constant rotation of the feed rolls.

Among the objects of my invention is the provision, in a press-driven roll feed having constantly rotating feed rolls, of an automatically operable adjustable release mechanism including an adjustable cam-plunger, operatively associated with the ram of the press, adapted for arresting and releasing the feeding movements of the stock at predetermined intervals during the uninterrupted operation of the press.

Another object of my invention resides in the provision of a novel release mechanism for roll feeds having upper and lower feed rolls which are constantly rotated by the press during its operation, and wherein the upper feed roll is mounted on a pair of spring-pressed vertically movable end bearings and both of which bearings are adapted to be simultaneously intermittently lowered by the novel release mechanism to thereby lower the upper roll, without interrupting its constant rotation, to thus instantly release the forward feeding movement of the stock during either the downward or upward movement of the press ram; and including means for raising the upper feed roll out of frictional contact with the stock to arrest the forward feeding movement of the stock.

With the above and other objects in view, my invention consists in the novel combination, construction and arrangement of the parts and members shown in preferred embodiment in the attached drawings, described in the following specification and particularly pointed out in the appended claims.

In the drawings:

Fig. 1 is an elevation of a part of punch press showing an end view of a roll feed and release mechanism embodying my invention;

Fig. 2 is an enlarged plan view of the roll feed;

Fig. 3 is a vertical section taken on line 3—3 of Fig. 2;

Fig. 4 is a vertical section taken on line 4—4 of Fig. 2 showing the feed release mechanism in feeding position;

Fig. 5 is a vertical section taken on line 5—5 of Fig. 2;

Fig. 6 is a vertical broken section taken on line 6—6 of Fig. 2 showing the feed rolls in operative stock-feeding position, and

Fig. 7 is a part vertical section showing the supports for the rolls shown in the left-hand portion of the illustration in Fig. 6, but showing the left-hand cam shaft rotated into roll-lifting position.

Fig. 8 is an enlarged vertical section of the adjustable feed release plunger adapted to operate on the downward stroke of the press ram;

Figs. 9 and 10 are cross-sections taken on respectively lines 9—9 and 10—10 of Fig. 8; and

Figs. 11 to 17, inclusive, are diagrammatic illustrations showing the progressive operating positions and movements of the feed release plunger for controlling the arrested position and released movement of the stock during the downward and upward movement of the release plunger.

The adjustable plunger illustrated in Figs. 8 to 17, inclusive, is adapted to release the movement of the stock by the rolls of the feed at selected points of the downward stroke of the press and for adjustably variable periods of time before the press performs its operation upon the stock.

Fig. 18 is an enlarged vertical section of the adjustable feed release plunger adapted to operate on the upward stroke of the press ram;

Figs. 19 and 20 are cross-sections taken on respectively lines 19—19 and 20—20 of Fig. 18; and

Figs. 21 to 27, inclusive, are diagrammatic illustrations showing the progressive operating positions and movements of the feed release plunger adapted to release the movement of the stock by the rolls of the feed at selected points of the upward stroke of the press and for adjustably variable periods of time after the press has performed its operation upon the stock.

Referring to the several illustrations in the attached drawings, 10 indicates generally a portion of a punch or die-operating press having a fly wheel 11 mounted on the crankshaft 12. An interchangeable sprocket 13 is removably mounted on one end of the crankshaft 12 and transmits rotary power by means of the chain drive 14 to an interchangeable sprocket 15 removably mounted on the feed drive shaft 16.

A tightener for the drive chain 14 is provided which consists of an arm 17 pivotally mounted on the tightener shaft 18.

The chain tightener shaft 18 is adjustably supported near one end thereof in a split bearing 19

provided with a tightening screw 20 for securing the shaft in proper stationary adjusted position.

The lower end of the chain tightener arm 17, as shown in Fig. 1, is adapted to be adjustably clamped to the free end of the shaft 18 and at such lower end carries a rotatable sprocket 21 for the drive chain 14 which passes through an open portion in the arm 17 and thence under the sprocket 22 which is rotatably mounted on the outer or free end of the arm 17.

The feed drive shaft 16 is rotatably mounted in a pair of bearings 23 formed integrally with the base 24 of the feed.

Under the removable housing cap 25 which is secured to the base 24, as by screws 26, is a bevel pinion 27 which is secured to the feed drive shaft 16 and operatively in mesh with a bevel gear 28 secured to the shaft extension 29 of the lower feed roll 30.

Mounted adjacently to the bevel gear 28, and rigidly secured to the lower feed roll shaft extension 29, is a spur gear 31 which is arranged to be in constant mesh with the spur gear 32 rigidly connected to one end of the shaft extension 33 of the upper feed roll 34.

The opposite end of the lower feed roll 30 is supported on the shaft extension 29^A and the similar end of the upper feed roll 34 is supported on the shaft extension 33^A.

The shaft extensions of the lower feed roll 30 are rotatably mounted in the cast base 24, but the shaft extensions 33 and 33^A of the upper feed roll are mounted in vertically movable bearings 35 having central upstanding integral studs 36 disposed within the lower ends of the coil springs 37.

The two coil springs 37 are mounted within the inverted cups 38 of the feed cap casting 39. These springs 37 exert pressures on top of the bearings 35 to normally retain the upper feed roll in operative or stock-feeding position.

The pressure of the springs 37 upon the upper feed roll is adjustable through the screws 40 which are threaded into the top of the cup portions 38 and the lower ends of these screws 40 abut with washers 41 which are positioned on the upper ends of the springs 37.

Lubrication of the upper feed roll shaft extensions 33 and 33^A, and the bearings 35 is supplied from the cups 42 which discharge the lubricant through central passages in the screws 40, the lower ends of which are provided with tubular extensions 43 extended downwardly into the lubricant-retaining cups 44 which are mounted upon the studs 36 and discharge the lubricant through suitable passages in the studs 36 to lubricate the shaft extensions 33 and 33^A and bearings 35 of the upper feed roll 34.

The cap casting 39 is secured to the base 24 by screws 45.

A resilient brake and guide for the stock which is to be passed through the feed is provided, as shown in Figs. 1, 2, 3 and 5, and consists of a vertically adjustable platform 46 in the form of a flat bar having depending pins 47 adjustably secured to the base 24 by screws 48. The stock, indicated by the letter S, which is to be fed from a reel is passed over the bar platform 46 under a brake plate 52 mounted above the bar 46 and having screws 49 with heads disposed beneath the lower face of the bar 46 and wing type tightening nuts 50 exerting pressure upon the upper ends of the coil springs 51, the lower ends of which springs press the brake plate 52 against the material or stock S to be fed to the press to

insure against any free longitudinal movement of the stock when the upper feed roll 34 is raised to arrest the feeding of the stock before or during the operation of press upon the stock.

5 Laterally adjustable guiding means, for the stock passing through the feed, is provided in the two metal blocks 53 which are slidably adjustably mounted on the bar 46. These guide blocks 53 are adapted to be adjusted at both 10 sides of the stock and screws 54 are provided for securing said blocks to the bar 46 in desired adjusted guiding positions.

As shown in Figs. 3, 5, 6 and 7, the upper feed roll bearings 35 are supported within vertical 15 slots of the base 24 and rest on the recessed portions 55 of the two roll-lifting shafts 56 which extend transversely to the axes of the feed rolls and are adapted for oscillatory movement within the base 24.

20 Both of the roll-lifting shafts 56 are arranged to extend outwardly of one end of the feed for connection thereto of the oscillatable arms 57 the free ends of which extend into pivotal connection with the forked ends of the connecting link 58.

To permit manual release of the upper feed 30 roll from frictional stock-feeding contact with the stock, as for example during the initial insertion and adjustment of the stock into proper position in the feed, a manually operable arm 59 is provided which is pivotally mounted on the outer end of a pin 60 secured within the ear 61 formed integrally with the cap casting 39.

The inner end of the manual release arm 59 35 carries a rotatable roller 62 which is arranged to ride upon an angularly disposed portion of the link 58 and when the manual release arm 59 is raised, as shown by the broken lines in Fig. 1, the roller 62 will exert pressure upon the link 40 58 to cause it to shift to the right, as viewed in Fig. 1, to thereby oscillate the arms 57 and the cam shafts 56.

The partial rotation of the roll-lifting cam 45 shafts 56 will cause the corners of the recessed portions 55 to raise the bearings 35 so that the upper roll 34 which is supported thereon will be raised or moved upwardly from the lower roll against the pressure of the springs 37 to thereby disengage its contact with the stock.

50 To positively lock the upper roll 34 in the described manually raised position, a shallow arcuate recess 63 is provided within the lower end portion of the angular top edge of the link 58 and this recess 63 is adapted to receive therein the roller 62 to thus retain the arm 59 in raised position until such arm 59 is forcibly moved into lowered position.

The automatic roll release operation and the 60 novel features of construction associated therewith are illustrated in Figs. 1, 2, 3, 4, and 8 to 27, inclusive. A clamp-like arm 64 is frictionally or otherwise secured to the end extension of one of the cam shafts 56, as by a tightening nut 65 on the adjustable contact screw 66.

65 Formed integrally with the cap casting 39 is a rectangular hollow support 67 which extends outwardly of the side of the feed above the arm 64.

Pivotedly mounted on pin 68 of support 67 is a 70 centrally slotted operating arm 69 which carries within its slot a roller 70 and has a depending end 71 which is adapted, upon oscillating movement of the operating arm 69, to engage with the end of the screw 66 of the arm 64 to move

the arm 64 and cause partial rotation of the cam shaft 56 connected therewith.

Cooperating with the roller 70 mounted on the pivoted operating arm 69, and spaced from the roller 70, is a guide roller 72 which is rotatably mounted within the support 67 on the pin 73.

Securely mounted on the front face of the press ram 14 is a supporting plate 75 which is provided with a pair of spaced integral extensions 76 adapted to receive therebetween the release plunger supporting arm 77 which is pivotally adjustably supported on the pivot bolt 78 extending through extensions 76.

The construction and operation of the feed release mechanism shown particularly in Figs. 1, 2, 3, 4 and 8 to 17, inclusive, which is designed to control the feed of the stock by the feed rolls to the dies on the downward stroke of the press ram, may be described as follows:

The feed release plunger, generally indicated by numeral 79, consists of an exteriorly threaded tubular support 80 formed preferably with an integral nut-like head 81. This threaded tubular support 80 has threaded engagement with the supporting arm 77 and is vertically adjustable relatively to the dies 82 and to its supporting arm 77.

A nut 83 is provided for securely retaining the plunger support 80 in proper vertically adjusted position.

The plunger 79 is also bodily laterally adjustable, with its supporting arm 77, about the pivot bolt 78.

The threaded vertically adjustable support 80 includes a companion support 84 in the form of an elongated rod of circular cross-section which supporting rod 84 functions to support on its lower portion, the coacting operative cam-portions 85 and 86 of the feed release plunger.

Although preferably shown as separate elements to facilitate manufacture and assembly into various lengths of plungers for different feed requirements, it is obvious that the two cam-supporting elements 80 and 84 could readily be made in one piece.

The upper end of the supporting rod 84 is fixed to the nut portion 81 as by the transverse pin 87. The lower end portion 84^A is slightly decreased in diameter to provide a shoulder 84^B which acts as an abutment for the relatively stationary cam 86. The lower end of the rod support is threaded as at 84^C, to receive the securing nut 88 which, together with the shoulder 84^A, secures the lower or relatively stationary cam 86 to the lower end of the rod 84.

The upper cam 85 is slidably mounted on the supporting rod 84 and is movable relatively to the lower cam 86.

Both of the elongated cams 85 and 86 are preferably of rectangular cross-section and are provided with a circular passage extending therethrough for the rod 84. The opposed ends of the cams 85 and 86 are each provided with an annular recess 89 to receive the opposite ends of a coil spring 90 which acts to retain the upper cam 85 in normal position spaced from the lower cam 86 and in abutment with the adjustable member 91.

The upper movable cam 85 is preferably provided with a slightly enlarged upper end portion 85^A to permit the provision of an annular recess 85^B which is adapted to receive therein the lower end of a depending tubular extension 91^A formed integrally with the lower face of the adjustable member 91.

The adjustable member 91 has threaded connection with the support 80 and is adjustable vertically relatively to the lower end of the exteriorly threaded support 80 to vary the upper or normally raised position of the movable cam 85 whereby the gap between the cams 85 and 86 may be adjustably varied to thereby vary the time during which the stock is fed to or through the press dies, as hereinafter more fully explained.

The cam gap adjusting member 91 is adapted to be secured in proper adjusted position by a set screw 92.

The lower cam 86 is usually positioned in most operations between the feed release means rollers 70 and 72 when the press ram and the dies 82 have reached their uppermost positions and its cam faces 86^A are maintained in proper aligned or face contact with the feed rollers 70 and 72 by the securing nut 88.

Obviously, some means must be provided for maintaining the cam faces 85^C, of the upper movable cam 85, in proper vertical alignment with the cam faces 86^A of the lower cam 86, and to accomplish this, I provide the lower cam 86 with a pair of upwardly extended arms 86^B, preferably formed integrally with and at opposite sides of the cam 86. These extended flat arms 86^B engage opposite sides of the movable cam 85 and retain it in alignment with the lower cam 86 so that it cannot rotate about its supporting rod 84.

It will be noted that the retaining arms 86^B are narrower than the width of cams between their cam faces so that these arms 86^B cannot be engaged by the feed control rollers 70 and 72.

The above-described type of plunger shown in Figs. 1, 2, 3, 4, and 8 to 17 inclusive, is so designed and so adjustable that it can be readily adapted to control the feed of various desired lengths of stock to the press dies during practically any part of the downward stroke of press ram.

From the above description and attached illustrations it will be apparent that the alignment of the plunger 79 with the feed control rollers 70 and 72 is readily attained through the lateral pivotal adjustment of the plunger supporting arm 77.

In most operations, and as herein preferably illustrated in Figs. 11 to 17, inclusive, the uppermost position of the plunger 79 is such that the lower cam 86 is positioned between the feed rollers 70 and 72 and the feed is not feeding the stock S to the press dies due to partial rotation of the shafts 56, against the pressure of springs 37 upon the upper feed roll bearings 35, into the roll-lifting position illustrated in Fig. 7.

When the lower cam 86, or the upper cam 85, is positioned between the rollers 70 and 72, the feed rolls 30 and 34 are inoperative to feed the strip of stock S. The feeding of the stock to the press dies occurs only when the plunger 79 is moved down to such extent that the spaced portion between the cams 85 and 86 is positioned between the rollers 70 and 72.

As soon as the spaced portion between cams 85 and 86 has passed or entered slightly below the horizontal axis of the roller 70, the roller 70 will be released from contact with cam 86 and it and its supporting arm 69 will be caused to be moved toward the plunger by the movement of the arm 64 toward the plunger due to the pressure of springs 37 against the bearings 35 of the upper feed roll to thereby lower the upper

rotating feed roll 34 into frictional feeding contact with the stock S. The feeding of the stock S to the press dies will continue until the plunger has moved downwardly to interpose the upper cam 85 between the rollers 70 and 72 whereupon the roller 70 and its supporting arm 69 will be moved away from the plunger to cause the depending end 71 of arm 69 to move the arm 64 to partially rotate both of the roll-lifting shafts 56 through the medium of the arms 57 and their connecting link 58. The movement of both of the shafts 56 into roll-lifting position will cause their seats 55 to tilt and raise the upper roll 34 from frictional feeding engagement with the stock S to arrest its movement.

During the continued downward movement of the upper cam 85 between the rollers 70 and 72, and while the stock S is in stationary position, the dies 82 will perform their operation upon the stock.

The movement of the plunger into stock feeding and die-operating positions is illustrated in Figs. 11, 12 and 13. In Fig. 11 the plunger is shown in its uppermost position just before the press ram and plunger start on their downward movement. The plunger is shown in its descent while in the stock-feeding portion of its cycle of operation, while in Fig. 13 the plunger is shown in its lowermost position with its upper cam interposed between the rollers 70 and 72, and after the dies have performed their work upon the stock.

During the downward movement of the plunger as illustrated by the progressively advanced positions shown in Figs. 11, 12 and 13 above-described, the two cams 85 and 86 are retained in spaced position by the coil spring 90 or, in other words, the upper cam 85 is supported in proper spaced position above the lower cam 86 by the spring 90 and the distance between the opposed ends of these cams 85 and 86 determines and controls the length of stock which shall be fed to the dies.

Obviously, the duration of the feeding movement of the stock, or length of stock fed to the dies, as well as the time or starting and stopping points of such stock-feeding movement may be varied and adjusted to the desired requirements, as for example, by varying the relative lengths of cams 85 and 86 and the space between them.

In the plunger under consideration, illustrated in Figs. 8 to 17, inclusive, means for varying the length of material fed to the dies, to a predetermined extent, is provided in the adjustable nut-like member 91. As shown particularly in Fig. 8, the illustrated plunger may be adjusted to feeding a longer piece of stock to the dies by releasing the cap screw 92 and screwing the nut-like member 91 upwardly on the threaded support 80 to thereby increase the length of the gap, or distance, between the opposed ends of the cams 85 and 86. The spring 90 will raise the cam 85 as the member 91 is moved upwardly and will retain such cam 85 in the desired raised position, however, the extent of such increase in length of stock fed is limited by the engagement of the threaded support 80 with bottom of the recess 85^B. Obviously, the member 91 provides means affording precision adjustment of the length of stock fed to the dies in addition to the adjustment of such stock length provided by the normal distance between the opposed ends of the cams 85 and 86.

Referring to the return or upward stroke operation of the press ram and plunger as illustrated

in Figs. 14 to 17, inclusive, Fig. 14 shows the plunger in its ascent at the moment when the lower cam 86 has engaged the lower end of the upper cam 85. It will be noted that while the support 77 and plunger-supporting portion 80 have been raised in the initial upward stroke of the press ram, the upper cam 85 is still in the same lowermost position shown in Fig. 13 when the plunger reached its lowermost position on the downward stroke of the press ram. This closing operation of the cam gap is made possible by the retainment of the upper cam 85 in stationary position by the pressure exerted against it by the roller 70 transmitted from the coil springs 37.

In the continued upward movement of the plunger, after the abutment of the lower cam 86 with the upper cam 85, the plunger will continue to be bodily raised with the two cams in closed or abutted position until the abutting ends have passed the horizontal axis of the rollers 70 and 72 whereupon the upper cam 85 will be released for upward movement, by the pressure of coil spring 90, into normal raised position spaced from the lower cam 86. Fig. 15 shows the plunger in its upward movement with the two cams still in closed position but just prior to the slightly advanced position shown in Fig. 16 wherein the abutted cam ends have passed the horizontal axis of the rollers 70 and 72 to permit release of the upper cam 85 into its normal raised position. Fig. 17 shows a still further advanced upward movement of the plunger prior to its uppermost position shown in Fig. 11 at the beginning of another cycle of operation.

The construction and operation of the feed release mechanism shown particularly in Figs. 18 to 27, inclusive, which is designed to feed the stock to the dies on the upward stroke of the press ram, may be described as follows:

The feed release plunger, generally indicated by numeral 93, consists of an exteriorly threaded tubular support 94 formed preferably with an integral nut-like head 95. This threaded tubular support 94 has threaded engagement with the supporting arm 77 and is vertically adjustable relatively to the dies 82 and to its supporting arm 77.

A nut 96 is provided for securely retaining the plunger support 94 in proper vertically adjusted position.

The plunger 93 is also bodily laterally adjustable, with its supporting arm 77, about the pivot bolt 76.

The threaded vertically adjustable support 94 includes a companion support 97 in the form of an elongated rod of circular cross-section which supporting rod 97 functions to support, on its lower portion, the coacting or cooperative cam-portions 98 and 99 of the feed release plunger.

Although preferably shown as separate elements to facilitate manufacture and assembly into various lengths of plungers for different feed requirements, it is obvious that the two cam-supporting elements 98 and 99 could readily be made in one piece.

The upper end of the supporting rod 97 is threaded to the securing nuts 100 and 101.

The lower end of the threaded support 94 is supported in the annular recess 98^B formed in the enlarged head 98^A of the upper cam 98 which is fixed to the rod 97 by the pin 102. The lower end of the rod support 97 is extended and threaded as at 97^A, to receive the securing nuts 103 and 104 which adjustably support the lower or rela-

tively movable cam 99 on the lower end of the rod support 97.

The lower cam 99 is slidably mounted on the supporting rod 97 and is movable relatively to the upper cam 98.

Both of the elongated cams 98 and 99 are preferably of rectangular cross-section and are provided with a circular passage extending therethrough for the rod 97. The opposed or adjacent ends of the cams 98 and 99 are each preferably provided with an annular recess 105 to receive the opposite ends of a coil spring 106 which positively retains the lower cam 99 in normal position spaced from the upper cam 98 and in abutment with the cam-gap adjustment nut 103 and its lock nut 104.

The threaded bottom end of the rod support 97 and the nuts 103 and 104 afford vertical adjustment of the lower movable cam 99 whereby the gap between the cams 98 and 99 may be adjustably varied to thereby vary the time during which the strip of material S is fed to or through the press dies, as hereinafter more fully explained.

The lower cam 99 is usually positioned in most operations between the feed rollers 70 and 72 when the press ram and the dies 82 have reached their uppermost positions.

When the plunger 93 has moved downward to the extent when the lower cam 99 has passed beyond the horizontal axis of the feed release means rollers 70 and 72, some means must be provided for maintaining the cam faces 99^A of the lower movable cam 99 in proper vertical alignment with the cam faces 98^A of the upper cam 98, and to accomplish this, I provide the upper cam 98 with a pair of downwardly extended arms 98^B, preferably formed integrally with and at opposite sides of the cam 98. These extended flat arms 98^B engage opposite sides of the movable cam 99 and retain it in alignment with the upper cam 98 so that it cannot rotate about its supporting rod 97.

It will be noted that the retaining or guide arms 98^B are narrower than the width of cams between their cam faces so that these arms 98^B cannot be engaged by the feed control rollers 70 and 72.

The above-described type of plunger shown in Figs. 18 to 27 inclusive, is so designed and so adjustable that it can be readily adapted to control the feed of various desired lengths of stock to the press dies during practically any part of the upward stroke of press ram.

From the above description and attached illustrations it will be apparent that the alignment of the plunger 93 with the feed control rollers 70 and 72 is readily attained through the lateral pivotal adjustment of the plunger supporting arm 71.

In most operations, and as herein preferably illustrated in Figs. 21 to 27, inclusive, the uppermost position of the plunger 93 is such that the lower cam 99 is positioned between the feed rollers 70 and 72 and the feed is not feeding the stock S to the press dies due to partial rotation of shafts 56 into the roll-lifting position illustrated in Fig. 7.

When the lower cam 99, or the upper cam 98, is positioned between the rollers 70 and 72, the feed rolls 33 and 34 are inoperative to feed the strip of stock S. The feeding of the stock to the press dies occurs only when the plunger 93 is moved up to such extent that the spaced portion between the cams 98 and 99 is positioned between the rollers 70 and 72.

In the downward stroke of the press, the plunger 93 will move downwardly and in such movement the lower movable cam 99 will be retained in stationary position between the rollers 70 and 72, due to the pressure exerted by the roller 70 against it, until the upper cam 98 engages the lower cam 99 whereupon as the plunger continues its downward movement both of the cams 98 and 99 acting as one continuous cam, will continue to retain the roller 70 and its arm 69 and roller-lifting mechanism in the same position wherein the upper roller 34 is in lifted position so that the strip of material S is maintained in stationary position. The above-described movement of the plunger 93 is illustrated in Figs. 21, 22, and 23.

As soon as the junction between the cams has passed below the horizontal axis of the roller 70, the lower cam 99 will be released to drop into its normal position at rest of the nut 103 but the roller 70 and its arm 69 will be retained in the feed-roller lifting position by the upper cam 98. This position is shown in Fig. 24.

It may here be stated that in the type of feed control illustrated by Figs. 8 to 17, inclusive, and also in the type illustrated in Figs. 18 to 27, inclusive, the operation of the dies upon the stock S occurs after the lower end of the upper cam has passed beyond the horizontal axis of the roller 70 while the upper cam is still in its downward movement.

After the plunger has reached its lowermost position, as for example, the position illustrated in Fig. 25, which is also the lowermost position of press ram and dies carried thereon, the ram, dies and plunger will reverse their movement and move upwardly.

In the upward movement of the plunger, the upper cam 98 will continue to maintain the roller 70 and its associated roll-lifting mechanism in arrested feeding position until the lower end of the upper cam 98 has passed upwardly beyond the horizontal axis of the roller 70 when the roller 70 is permitted to move toward the plunger 45 within the gap portion between the upper and lower cams. This position is shown in Fig. 26.

The feeding movement of the strip of stock S will continue during the upward movement of the plunger until the lower cam 99 again engages the roller 70 and moves it and its arm 69 and associated feed mechanism into roll-lifted position when the movement of the strip of stock will be arrested and retained in stationary position while the plunger moves into its uppermost position.

Obviously, the duration of the feeding movement of the stock, or length of stock fed to the dies, as well as the time or starting and stopping points of such stock-feeding movement may be varied and adjusted to the desired requirements, as for example, by varying the relative lengths of cams 98 and 99 and the space between them. The space between the cams is adjustable by turning the nut 103 to move it upwardly to shorten the feed gap or by turning it to move it downwardly on the rod 97 to lengthen the feed gap.

The spring 106 might be dispensed with since the lower cam 99 will fall by gravity after its upper end has passed beyond the horizontal axis of the rollers 70 and 72 in the downward movement of the plunger, but I prefer to employ such spring 106 to insure a positive and quick downward movement of the lower cam immediately upon its release from the rollers 70 and 72.

I claim:

1. In a machine adapted to perform work upon

a strip of material fed thereto by an automatic feed having movable means thereon for arresting and releasing the feeding movement of the material; control means operatively associated with said machine for controlling the operation of said feed arresting and releasing means, said control means including a reciprocating member having a pair of normally spaced but relatively movable cams thereon adapted to successively engage and move said movable means to successively arrest the movement of said material during spaced intervals of time during the movement of said member in one direction and to maintain the arrested or stationary position of the material upon the movement of one of said cams into contiguous alignment with the other cam during the movement of said member in the opposite direction.

2. The control means defined in claim 1 and including said movable feed means having retaining means for engaging one of said cams to arrest its movement during a portion of the movement of said reciprocating member in said opposite direction to thereby permit the other one of said cams to be moved with said reciprocating member into abutment with said arrested cam to form a combined elongated cam for contiguously engaging said retaining means during the remaining portion of the movement of said reciprocating member in said opposite direction thereby retaining said movable feed means in the position for maintaining the stationary position of the strip material.

3. The control means defined in claim 1 and including resilient means on said reciprocating member retaining said cams in relatively spaced position during the movement of said reciprocating member in said one direction, and including said movable feed means having frictional means for engaging one of said cams to arrest its movement against the pressure of said resilient means and during a portion of the movement of said reciprocating member in said opposite direction to thereby permit the other one of said cams to be moved into abutment with said arrested cam to form a combined elongated cam for contiguously engaging said retaining means during the remaining portion of the movement of said reciprocating member in said opposite direction thereby retaining said movable feed means in the position for maintaining the stationary position of the strip material.

4. The control means defined in claim 1 and including means on said member for adjustably varying the normal space between said cams.

5. The control means defined in claim 1 and including screw-threaded means on said member for adjustably varying the space between said cams, resilient means on said reciprocating member normally retaining said cams in relatively spaced position during the movement of said reciprocating member in said one direction, and including said movable feed means having a pair of relatively movable rollers for frictionally engaging one of said cams to arrest its movement against the pressure of said resilient means during a portion of the movement of said reciprocating member in said opposite direction to thereby permit the other one of said cams to be moved into abutment with said arrested cam to form a combined elongated cam for contiguously engaging said rollers during the remaining portion of the movement of said reciprocating member in said opposite direction thereby retaining said movable

feed means in the position for maintaining the stationary position of the strip material.

6. Control means for a press having a reciprocating ram and dies thereon adapted to perform work on a strip of material fed thereto by a roll feed provided with a pair of continuously rotating rolls for frictionally engaging and feeding the material to said dies and including movable means for releasably separating said feed rolls at predetermined intervals for arresting and releasing the feeding movement of the material during the continuous rotation of said feed rolls; said control means for controlling the feeding movement of the strip of material to said dies including a reciprocating plunger adapted for reciprocation by the press, said plunger including an elongated support, a pair of normally spaced cams mounted on and movable with said support, one of said cams being fixed relatively to said support and the other one of said cams being movable relatively to said support and to said relatively fixed cam, said cams being adapted to successively engage and move said movable means to successively separate said feed rolls to thereby successively arrest the movement of said strip of material during the movement of the plunger in one direction, said feed roll separating means including cam-arresting means adapted to arrest the movement of said movable cam during a portion of the movement of said plunger in said opposite direction to thereby permit the other one of said cams to be moved into abutment with said arrested cam to form a combined elongated cam for contiguously slidably engaging said cam-arresting means during the remaining portion of the movement of the plunger in the opposite direction to thereby maintain the arrested or stationary position of the strip of material during such opposite movement of the plunger.

7. The control means defined in claim 6 and including resilient means on said plunger for retaining said movable cam in spaced relation to said fixed cam during the movement of the plunger in said one direction.

8. The control means defined in claim 1 wherein in said reciprocating member includes an elongated rod and wherein one of said cams is slidably mounted on said rod but movable relatively to the other of said cams during the movement of said member in said opposite direction, and including a pair of spaced extensions extending from one of said cams to embrace a pair of opposite sides of the other of said cams to thereby retain said slidably mounted cam against rotation on said rod.

9. The control means defined in claim 6 wherein in said plunger includes an elongated rod and wherein said movable cam is slidable on said rod into abutment with said fixed cam during the movement of said plunger in said opposite direction, and including means for retaining said movable cam in cam-face alignment with said fixed cam.

10. The control means defined in claim 6 including adjustable means on said plunger for varying the normal space between said cams to thereby adjustably vary the fed length of the strip of material.

11. The control means defined in claim 6 and including a laterally adjustable support on said ram for said plunger, and means for adjusting said plunger vertically relatively to said laterally adjustable support.

12. The control means defined in claim 6 and wherein said ram includes a laterally adjustable

support for said plunger, and including said plunger comprising an elongated exteriorly screw-threaded tubular member in threaded engagement with said laterally adjustable support, a rod extending through and below said tubular member and connected to said tubular member, said rod having a shoulder and a threaded lower end provided with a securing nut, said fixed cam being mounted on said rod and retained against movement relatively to said rod by its engagement at one end with said rod shoulder and at its other end with said nut, said movable cam being slidably mounted on said rod above said fixed cam, a spring coiled about said rod having its ends in abutment with opposed ends of said cams, and extensions on one of said cams extended to embrace the other of said cams to retain said cams in cam-face alignment.

13. The control means defined in claim 6 and wherein said ram includes a laterally adjustable support for said plunger, and including said plunger comprising an elongated exteriorly screw-threaded tubular member in threaded engagement with said laterally adjustable support, a rod extending through and below said tubular member and connected to said tubular member, said rod having a shoulder and a threaded lower end provided with a securing nut, said fixed cam being mounted on said rod and retained against movement relatively to said rod by its engage- 30

ment at one end with said rod shoulder and at its other end with said nut, said movable cam being slidably mounted on said rod above said fixed cam, a spring coiled about said rod having its ends in abutment with opposed ends of said cams, extensions on one of said cams extended to embrace the other of said cams to retain said cams in cam-face alignment, and a screw-threaded adjustment member in threaded engagement with said tubular member for adjustably varying the normal space between said cams.

14. The control means defined in claim 6 and wherein said ram includes a laterally adjustable support for said plunger, and including said plunger comprising an elongated exteriorly screw-threaded tubular member in threaded engagement with said laterally adjustable support, a rod supported within said tubular member and extending below said tubular member and having its lower end threaded for a nut thereon, said movable cam being supported on said nut and slideable on said rod, said fixed cam being secured to said rod in spaced position above said movable cam, and a pair of spaced extensions on one of said cams extended to embrace the other of said cams to maintain said cams in cam-face alignment.

CHARLES V. ST. LOUIS.
